H. B. RUMMELL,
SPARK PLUG,
APPLICATION FILED SEPT 12, 1917.

Patented Feb. 17, 1921.

UNITED STATES PATENT OFFICE.

HARRY B. RUMMELL, OF FINDLAY, OHIO.

SPARK-PLUG.

1,381,029.

Specification of Letters Patent. Patented Feb. 17, 1920.

Application filed September 12, 1917. Serial No. 190,986.

To all whom it may concern:

Be it known that I, HARRY B. RUMMELL, a citizen of the United States, residing at Findlay, in the county of Hancock and State of Ohio, have invented certain new and useful Improvements in Spark-Plugs; and I do hereby declare the following to be a full, clear, and exact description of the invention, such as will enable others skilled in the art to which it appertains to make and use the same.

This invention has for its object to provide an improved spark plug for explosive engines, in which the center electrode is formed in two sections spaced an adequate distance apart to provide an internal spark gap designed to increase the efficiency of the plug and prevent short circuiting when the plug is fouled.

Another object is the provision of means for rigidly anchoring the sections of the center electrode in position in the insulator and also for maintaining them in predetermined spaced relation to each other.

With these and other objects in view, the invention consists in the novel construction, combination and arrangement of parts as will be hereinafter specifically described, claimed and illustrated in the accompanying drawing, in which:

Figure 1 represents a side elevation of the improved spark plug,

Fig. 2 represents a longitudinal sectional view therethrough,

Fig. 3 represents a transverse sectional view in the plane of the line 3—3 of Fig. 2,

Fig. 4 represents a fragmentary transverse sectional view through the center portion of the plug, showing the cylindrical tubular insulator in detail.

Referring to the drawing in detail, where similar reference numerals designate corresponding parts throughout the several views, the numeral 5 indicates the body of the plug which is provided at one end with a series of wrench jaw-engaging faces and is reduced and externally screwthreaded at its opposite end, as indicated at 6, to facilitate its insertion in the spark plug port of the cylinder of an engine (not shown). The plug body, as usual, is of hollow construction and is provided with the internal bore 7, which is restricted in its diameter at the reduced terminal 6, providing an internal shoulder 8.

An insulator 9, constructed of porcelain,

or other desired material, is inserted in the body 5 and projects from the polygonal terminal thereof. The central portion of the insulator is formed with an integral flange 60 which is seated against the shoulder 8 and a gasket 10 is interposed between the face of the flange and the shoulder 8 to insure against leakage of the explosion or products of combustion. 65

The relatively large terminal of the plug body is formed with internal screwthreads receiving a ring nut 11, which co-acts with the flanged medial portion of the insulator 9 to rigidly anchor the latter in position 70 in the plug body. A gasket 22 is preferably interposed between the nut and the flange of the insulator to render the spark plug leak-proof.

The insulator 10 is formed with a longitudinal bore 13, extending throughout its entire length, and which is reduced at the end of the insulator adjacent the threaded terminal 6 of the plug body, providing the internal shoulder 14, which faces toward the 75 relatively large end of the body 5. The inner section 15 of the center electrode is fitted within the relatively small terminal of the bore 13 and projects a short distance within the relatively large portion thereof. The 80 inner terminal of the section 15 is formed with an anchoring flange 16 of circular formation and which is firmly seated against the internal shoulder 14 formed on the wall of the bore 13. The extreme inner 85 terminal of the section 15 is pointed, as indicated at 17, and is disposed in spaced relation to the adjacent pointed terminal 18 of the outer center electrode section 19, which latter is accommodated within the relatively 90 large portion of the bore 13 and is provided with a reduced inner terminal defining a shoulder 20. The reduced terminal of the outer electrode section 19, and the adjacent terminal of the section 15, are received with 95 in a separate tubular insulator 20, constituting a spacing element for maintaining the electrodes in predetermined spaced relation to prevent variance in the length of the spark gap 21 between the electrode sections. 100

The tubular insulator 20 is formed separately from the main insulator 9, and is inserted in the relatively large terminal of the bore 13, so as to facilitate removal of the electrode sections from the porcelain body, 105 when desired. 110

The end of the section 19 opposite the

section 15 is externally screwthreaded, as indicated at 22, and is fitted within an internally threaded recess formed in the hollow shank 23 of an anchoring cap 24, the apron 5 or flange of which latter is of frusto-conical formation and is firmly engaged with the correspondingly formed terminal 25 of the insulator 9, so as to firmly anchor the cap 24 in position thereon. A nut 26 for securing 10 the wire, or other conductor, to the center electrode is fitted upon the externally screwthreaded shank 23 and the outer electrode 27 of the spark plug is rigidly and electrically connected with the reduced 15 terminal 6 of the body 5, and is disposed in spaced relation to the adjacent terminal of the inner center electrode section 15.

What I claim is:

A spark plug including a hollow body, 20 an insulator mounted therein and provided with an axial bore enlarged at one end to provide an inner annular shoulder, an electrode section fitted in the relatively small portion of said bore and projecting into the 25 relatively large portion thereof, said elec-

trode section being provided with an outer annular shoulder spaced from its upper end and engaging the shoulder at the inner end of the enlarged portion of the bore so as to secure said section against downward movement, an outer electrode section fitted in the relatively large portion of the bore and provided at its inner end with a reduced terminal member disposed in alinement with the upper end of the first mentioned electrode 30 section and spaced therefrom, and a tubular insulating member fitting snugly in the enlarged portion of the bore of said insulator and engaging the shoulder of the first mentioned electrode section and the lower end 40 of the body portion of the electrode section mounted in the enlarged portion of the bore so as to maintain the two electrode sections in predetermined spaced relation.

In testimony whereof I affix my signature 45 in presence of two witnesses.

HARRY B. RUMMELL.

Witnesses:

MARY LAUBE,
RALPH R. MILLER.
